UNITED STATES PATENT OFFICE.

HARRY SAUVEUR, OF BERLIN, GERMANY.

SUBMERGED LIFTING PUMP FOR DEEP WELLS.

Application filed October 7, 1926, Serial No. 140,097, and in Germany October 5, 1925.

My invention relates to submerged lifting pumps for deep wells and more particularly to pumps of the type which are driven directly by electric motors. It has already 5 been proposed to introduce a gas under pressure into the casing of the motor to prevent penetration of the liquid to be raised into the casing through leaky stuffing boxes and the like which would cause damage to the windings of the motor.

It is an object of my invention to improve this method of protecting the motor by a compressed gas and to this end I introduce into the motor gas under pressure and regulate 15 the pressure in the motor to a given value in excess of the varying hydrostatic pressure under which the pump is submerged. The gas may be taken from a supply of compressed gas above ground.

20 The pressure in the motor can be regulated by various means, and in a preferred embodiment I provide a regulator influenced on one side by the pressure within the machine casing and on the other side by the 25 pressure of the liquid in the well surrounding the casing and an adjustable additional load so that the regulator stands in its normal position if the pressure within the casing is in balance with the pressure on the 30 outside of the casing and the pressure of the additional load. Therefore this additional load corresponds to the desired surplus of 35 pressure of the gas in the casing over the pressure of the liquid surrounding the casing. This additional load may be brought about by an adjustable spring.

A regulator operating on this principle 40 may be adapted to connect a gas supply under pressure with the motor as required to maintain the pressure therein within the limits defined above.

Any gas may be utilized which is of such a character as not to exert detrimental action on the parts of the motor, or on the gas or 45 liquid in the well, or to involve danger of explosion.

In the drawings affixed to this specification, a pump embodying my invention is illustrated diagrammatically by way of example.

50 Figure 1 is a diagrammatic elevation showing a plant in which a centrifugal pump is arranged below the motor, and gas is supplied from a supply of pressure above ground, and

Fig. 2 is a section of a regulator for the plant of Fig. 1, on a larger scale.

Referring now to the drawings, and first to Fig. 1, 45 is a well or shaft, for instance, an oil well, and 1 is the delivery pipe from 60 which the pump and motor unit is suspended. The unit is constituted by the motor 2 and the pump 5. In the present instance, the motor is arranged above the pump. 2' is the shaft of the motor 2 which extends 65 downwards through stuffing boxes 3 and imparts rotation to the pump 5 through a clutch 4. The pump may be of any suitable type and is here shown as a centrifugal pump. The pump draws oil from the well 70 as indicated by the arrow 6 and discharges it into the delivery pipe as indicated by the arrows 6'. 7 is a check valve in the delivery pipe 1.

The liquid level in the well 45 is subjected to considerable variations and an automatic regulator 17 is provided for regulating the gas pressure in the motor in conformity with the liquid head. The regulator is shown on a larger scale in Fig. 2. 18 75 is a pipe through which oil from the well 45 is admitted to the inside of the regulator 17 and 20 is a diaphragm which closes the under chamber of the regulator at the top. 19 is a spring interposed between an upper 80 and lower washer 19'. The upper washer engages the diaphragm 20 and the lower is supported by a set screw 19" in the bottom of the casing 17. The spring 19 is set for the desired pressure gradient before the 85 pump is lowered into the well. The gas pressure in the casing acts on a piston 22 on the top of the diaphragm 20. 37 is a chamber above the regulator casing 17 to which 90 gas under pressure is supplied from a compressor or the like, not shown, through a pipe 37'. 47 is a spindle on the piston 22, and 46 is a valve on the end of the spindle which controls an opening in the bottom of the chamber 37. 46' are ports in the wall 100 of the regulator casing through which gas from the chamber 37 is discharged into the motor 2 when the valve 46 opens which will occur when the pressure in the well increases due to the rising of the liquid level 105 therein. The valve remains open until the gas pressure above the diaphragm 20 corresponds to the increased pressure in the casing and the tension of spring 19 and closes when equilibrium has been reestablished. 110

When the pressure in the well decreases, the gas from the motor will gradually escape through leakage at the stuffing box 3.

I claim:

5 A submerged motor comprising a closed casing filled with a gas under pressure; means for supplying additional gas under pressure; and automatic means for regulat-

ing the gas pressure within the casing to maintain in the casing the gas pressure at a given surplus over the changing pressure in the fluid or material surrounding the casing.

In testimony whereof I have affixed my signature.

HARRY SAUVEUR.
